[57] **CLAIM**

The ornamental design for a housing for a flash device,
as shown and described.

DESCRIPTION

FIG. 1 is a front, right side perspective view of a housing
for a flash device showing my new design;

FIG. 2 is a top plan view thereof; and

FIG. 3 is a bottom, rear, left side perspective view
thereof.

The flash cube is shown in broken lines for illustrative
purposes only.

FIG. 1.

FIG. 2.

FIG. 3.
